US0D1021335S

(12) **United States Design Patent** (10) **Patent No.:** **US D1,021,335 S**
(45) **Date of Patent:** **** Apr. 9, 2024**

(54) **BREASTFEEDING COVER**

(71) Applicant: **Jared McDonnell**, Reno, NV (US)

(72) Inventor: **Jared McDonnell**, Reno, NV (US)

(73) Assignee: **Jared McDonnell**, Reno, NV (US)

(**) Term: **15 Years**

(21) Appl. No.: **29/834,884**

(22) Filed: **Apr. 14, 2022**

(51) **LOC (14) Cl.** **02-02**

(52) **U.S. Cl.**

USPC **D2/823**

(58) **Field of Classification Search**

USPC D2/823, 860, 861, 864

CPC A41D 1/215; A41B 13/103

See application file for complete search history.

(57) **CLAIM**

The ornamental design for a breastfeeding cover, as shown and described.

DESCRIPTION

FIG. 1 is a front view of a breastfeeding cover showing my new design;

FIG. 2 is a rear view of the breastfeeding cover;

FIG. 3 is a right side view of the breastfeeding cover;

FIG. 4 is a left side view of the breastfeeding cover;

FIG. 5 is a top view of the breastfeeding cover;

FIG. 6 is a bottom view of the breastfeeding cover; and,

FIG. 7 is a bottom front side perspective view of the breastfeeding cover.

The broken lines in the drawing figures are illustrative of stitching forming no part of the claimed design.

1 Claim, 4 Drawing Sheets
